HEATING APPARATUS

Thomas J. Kenny, Elkins Park, Pa.

Application May 2, 1955, Serial No. 505,337

6 Claims. (Cl. 219—34)

This invention relates to heating apparatus, and more particularly concerns heating devices that are used to heat passenger railroad cars.

More specifically, this invention relates to improvements in electric heating devices, and other types of heating apparatus, for instance steam heaters, and heater guards installed along the base of the inside wall of a railroad passenger car.

Various types of heating apparatus and heater guard devices have heretofore been used to warm the air in passenger railroad cars. Such devices have produced hot spots on the vertical covering thereof where the temperature has ranged as high as 270° F. and have burned passenger's legs and clothing, and melted pocketbooks and women's plastic overshoes. Heating apparatus which have used electric heating elements have been notably deficient in this respect. Others of such previous devices have failed to protect the heater elements from foreign objects such as papers, cigar wrappers, umbrellas and other articles that are likely to be thrust through the openings in the heater covering.

Accordingly it is one object of this invention to provide means whereby to overcome the aforementioned deficiencies of previous devices, means whereby hot spots are eliminated and the heater elements are protected. Another object of this invention is to lower the temperature of the heater guard without lowering the temperature of the heater elements. A further object of the present invention is to increase the stack height of the heating apparatus within the overall height limitations placed on the heating apparatus by reason of passenger railroad car construction design. A still further object of this invention is to increase the rate of air flow that passes the heater elements.

Another object of the present invention is to provide a heating apparatus of the convector type which will transfer the heat energy from an electric strip heater element to a maximum volume of air with the greatest degree of efficiency.

A further object of this invention is to convert electrical energy into heat energy to heat a maximum volume of air and to provide a maximum flow of unrestricted heated air.

A further object of the present invention is to provide a heating apparatus of the convector type which will foment a natural circulation of air through the heating apparatus to produce the largest volume of heated air at a predetermined temperature.

A still further object of this invention is to provide a heating apparatus having cover members which are maintained at a moderate temperature without mechanically moving the air such as by use of fans and similar devices.

Further objects and advantages will be apparent from the description which follows, having particular reference to a preferred embodiment of this invention as shown in the drawing, in which:

The drawing is a broken perspective view partly in

2

section of one end of the unit mounted along the inside wall of a railroad passenger car in the corner formed by the juncture of the inside wall and the floor of the car.

In the drawing there is shown an inside wall 21 of a railroad passenger car and a floor 22 of that car. A carpet 23 covers part of the floor 22. Mounted on inside wall 21 is a cover guard supporting angle bracket 24 which extends horizontally along the side of the car. Affixed to the cover guard supporting angle 24 by means of screws 25 is a cover guard or enclosure 26. Enclosure 26 is bent to form a first vertical surface 27, a first horizontal surface 28, a second vertical surface 31, and a second horizontal surface 32 attached to the cover guard supporting angle bracket 24. The upper portion of the first vertical surface 27 is provided with a plurality of elongated slots 33 to form a first air outlet designated generally by the numeral 34. Similarly, the upper portion of the second vertical surface 31 is provided with a plurality of elongated slots 35 to form a second air outlet designated generally as 36. The bottom of first vertical surface 27 is terminated at a distance short of the floor 22 to form an air inlet 37. The bottom edge of the first vertical surface 27 is turned outwardly from the center of the railroad car to form a flange 38 in order to present a smooth curved surface to possible contact with a passenger's foot or leg. Supporting bracket 41 is bolted to the bottom portion of the first vertical surface by bolt 42 and is screwed to the floor 22 of the car by screw 43. The supporting brackets 41, only one of which is shown in the drawing, are spaced along the floor of the car at intervals of about eighteen inches and together with the cover guard angle supporting bracket 24 serve to maintain the cover guard or enclosure rigidly in place.

Below the cover guard supporting angle bracket 24 is mounted a U-shaped bracket 44 which is bolted to inside wall 21 by bolts 45 and nuts 46. A bracket 47 is bolted to U-shaped bracket 44 by bolt 48 and nut 51, and a baffle 52 is supported within enclosure 26 between bracket 47 and U-shaped bracket 44 by the bolt 48 and nut 51. A first electric strip heater element 53 is mounted on bracket 47 by nut 54 and bolt 55. Between the head of bolt 55 and the electric strip heater element 53 there is provided an insulator 56 and between the electric strip heater element 53 and the bracket 47 there is provided an insulator 57. Two electric terminals 58 are mounted on the electric strip heater element 53 for attachment of wires 59 and 60 that transmit the electric power necessary to energize electric strip heater element 53.

Another bracket 61 is bolted to the U-shaped bracket 44 by nut 62 and bolt 63. A second strip heater element 64 is mounted on bracket 61 by nut 65 and bolt 66. Between the head of bolt 66 and the electric strip heater element 64 there is provided an insulator 67, and between the electric strip heater element 64 and the bracket 61 there is provided an insulator 68. Two electric terminals (not shown) are provided on the electric strip heater element 64.

The baffle 52 is positioned so that its upper edge 71 is contiguous with the upper portion of the first vertical surface 27. From here the baffle 52 follows a curve downwardly to pass between the inside wall 21 of the railroad car and the first electric strip heater element 53. An air space 72 is left between the baffle 52 and the first horizontal surface 28. Then baffle 52 follows a substantially vertical line to its place of attachment to U-shaped bracket 44 and bracket 47. From here the baffle 52 extends substantially horizontally to pass between the first heater element 53 and the second heater element 64. Then the baffle 52 curves downwardly to

pass between the second heater element 64 and the first vertical surface 27, terminating short of floor 22 to leave an air space 73 between said baffle 52 and the floor 22.

Similar heater element and baffle supports are provided at the other end of the heater elements 53 and 64 shown in the drawing, and a plurality of heater elements 53 and 64 are provided along the length of the inside wall 21 of the railroad passenger car.

The operation of this heater and heater guard will now be apparent. In accordance with the invention cool air, which will lie near the floor 22 of the railroad passenger car will enter air inlet 37. A portion of this air will be deflected by baffle 52 to the area surrounding the first heater element 53, there to be warmed and deflected by baffle 52 to first air outlet 34 for discharge into the car.

The other portion of the air from air inlet 37 will pass beneath baffle 52 through air space 73 to the area surrounding the second heater element 64, there to be warmed and then pass along the inside wall 21 to second air outlet 36 for discharge into the car.

In the preferred embodiment of the invention shown in the drawing the first heater element 53 is a 200 watt electric strip heater of 0.8 watt density (watts per square inch of emitting surface), and the second heater element 64 is an 800 watt electric strip heater of 3.2 watts density.

This arrangement of the apparatus as shown in the drawing has many advantages. The first vertical surface 27 is exposed to the radiant heat of only the smaller-capacity first heater element 53, since the baffle 52 shields the first vertical surface 27 from the radiant heat emitted by the larger capacity second heater element 64. This helps to keep the first vertical surface 27 at a moderate temperature. The baffle 52 and air space 72 help maintain the first horizontal surface 28 at a moderate temperature.

It has been found that making the enclosure 27 of aluminum results in lower surface temperatures than when enclosure 27 has been made of stainless steel.

Supporting the heater elements 53 and 64 on brackets extending a distance away from the inside wall 21 prevents hot spots from developing on the inside wall 21 and permits free passage of a volume of air from second heater element 64 to second air outlet 36.

The distance between the second heater element 64 and the second air outlet 36 is referred to in the art as the stack height. Increasing the stack height increases the stack effect, which is to increase the volume of air that passes the second heater element 64 in a certain time interval. This increased volume-rate of air results in a lower temperature of the air since the heat emitted by the second heater element 64 remains fixed. Positioning the second and larger capacity heater element 64 near the floor 22 of the car, and positioning the second air outlet 36 near the top of enclosure 26 accomplishes the object of providing maximum stack height and effect and of heating a large volume of air to the desired temperature without developing hot spots on the heating apparatus, including the heater guard.

In the preferred embodiment of the invention the elongated slots of the air outlets 36 and 34 are a $\frac{1}{2}$ inch wide and $\frac{1}{4}$ inches high, while the air inlet 37 is $\frac{1}{8}$ inches high. These dimensions may be varied somewhat but it is important to provide air outlets of adequate size, for the air outlet size, the baffle 52 and the stack height combine to permit free passage of air and to eliminate the stagnant hot air pockets which cause hot spots on the heating apparatus.

While I have disclosed a preferred embodiment of the present invention it will be understood that various modifications, including the use of equivalent means, are included within the broad outlines of the present invention, and it is intended that such modifications shall be included within the definition of the present invention as set forth in the appended claims. For instance the air

inlet 37 may be a plurality of elongated slots similar to the elongated slots 33 and 35 forming first air outlet 34 and second air outlet 36, respectively, and the baffle 52 may assume more of an S-shape.

Having thus described my invention, I claim:

1. Heating apparatus for mounting on the inside wall and floor of railroad passenger cars for warming the interior of said railroad passenger cars, comprising in combination an enclosure including a first and a second vertical surface and a first and a second horizontal surface, the second horizontal surface extending inwardly from the inside wall of the railroad passenger car substantially parallel to and spaced away from the floor, the second vertical surface extending downwardly from the inner edge of the second horizontal surface substantially parallel to and spaced away from the inside wall, the first horizontal surface extending inwardly from the lower edge of the second vertical surface substantially parallel to and spaced away from the floor and the second horizontal surface, the first vertical surface extending downwardly from the inner edge of the first horizontal surface substantially parallel to the inside wall and the second vertical surface, the first vertical surface having its lower edge spaced away from the floor to form an air inlet, the first vertical surface having a plurality of elongated slots in the upper portions thereof to form a first air outlet, the second vertical surface having a plurality of elongated slots in the upper portion thereof to form a second air outlet; a first electric strip heater element of about 0.8 watt density mounted within said enclosure between the first horizontal surface and the floor and positioned midway between the first vertical surface and the inside wall; a second electric strip heater element of about 3.2 watts density mounted within said enclosure below the first electric strip heater element and within the lower one-third of the first vertical surface; a curved baffle contiguous to the first vertical surface and curving downwardly to pass between the inside wall and the first electric strip heater element, then extending substantially horizontally to pass between the first and the second electric strip heater elements, then extending downwardly to pass between the second electric strip heater element and the first vertical surface and terminating short of the floor to leave an air space between said baffle and the floor; whereby to admit cool air through the air inlet, pass a portion of said cool air to the area adjacent the first electric strip heater to warm the air, the warm air rising to be deflected by said baffle to said first air outlet for discharge into the railroad passenger car; whereby to pass a portion of said cool air behind said curved baffle to the area adjacent the second electric strip heater to warm the air, said warm air rising to said second air outlet for discharge into the railroad passenger car; and whereby to maintain said enclosure at such a temperature so as to prevent burning of passengers and their clothing.

2. Heating apparatus for mounting on the inside wall of railroad cars and the like, comprising a cover guard having an air inlet formed therein, said cover guard including a first and a second vertical surface spaced apart from each other and joined together by a connecting surface extending from the lower edge of the second vertical surface to the upper edge of the first vertical surface, each of said vertical surfaces having an air outlet formed therein; a first and a second heater element fixedly mounted and positioned inside the cover guard and spaced therefrom, means for energizing said heater elements, and baffle means mounted within said cover guard for shielding the second vertical surface, the connecting surface, and the second heater element from the first heater element.

3. The heating apparatus defined in claim 2, wherein said first heater element is positioned above said second heater element.

4. The heating apparatus defined in claim 3, wherein said second heater element is of greater heating capacity than said first heater element.

5. The heating apparatus defined in claim 2, wherein said connecting surface is substantially horizontal.

6. The heating apparatus defined in claim 5, wherein said cover guard is also provided with a second horizontal surface which is joined to the top edge of said second vertical surface.
